GARMENT HANGER

Harold C. Cook, Sr., Long Island City, N. Y.

Application July 17, 1946, Serial No. 684,151

13 Claims. (Cl. 223—91)

1

This invention relates to a garment hanger. The standard garment hanger consists of a hook for suspending the hanger, shoulder pieces to receive a coat, and a rod connecting the ends of the shoulder pieces, over which an additional garment may be hung. It is difficult to hang garments over the cross rod; it is more difficult to remove them from the rod, and it is difficult indeed to remove a garment from the cross rod when a coat is on the shoulder pieces. In order to accomplish this successfully, it is generally necessary to remove the hanger from the support, remove the coat from the hanger, and then remove the garment from the rod. That clumsy necessity is one of the minor annoyances which is encountered frequently because it is frequently desired to remove trousers or a skirt from the hanger without disturbing the coat and without removing the hanger from its support.

It is an object of this invention to construct a garment hanger having shoulder pieces adapted to receive the coat and having removable clamps adapted to suspend other garments, which will be readily removable when removal is desired, but which will not be accidentally disengaged by the normal handling to which such garment hangers are subjected.

A particular object of the invention is to construct a device of the character described in a plurality of modifications adapted to particular uses and to particular methods of construction.

The above and further objects and novel features of the present invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a vertical elevational view of a preferred form of hanger embodying the principles of the invention;

Fig. 2 is a perspective detail of the embodiment shown in Fig. 1;

Figs. 3 and 4 are respectively an end elevation and a vertical section showing a preferred method of attaching the springs to the clamping rods;

Figs. 5 and 6 are respectively a vertical section and a side elevation of an alternate method of

2

attaching the spring ends to the clamping rods; Figs. 7 and 8 are respectively detail views of a modified form of clamping rod and of the means of attaching the springs thereto;

Fig. 9 is an end elevational view of a modified form of detachable trouser hanger;

Fig. 10 is a perspective view of an end of another modification; and

Fig. 11 is a perspective view of an end of yet another modification.

In the drawings, the numerals 10, 10' indicate shoulder pieces of a garment hanger that are shaped to receive and maintain the set of a coat. These pieces may conveniently be made of wood, although they may also be made of other materials, and may be held together by one or more metal pieces 11 of curved shape that are driven into the pieces 10, 10' across the joint 12. The strength of a hanger so constructed is adequate for ordinary purposes. A hook 13 projects upward from the hanger and is employed to suspend it from the usual rod that is employed in clothing closets for that purpose. The undersides of the shoulder pieces are provided with oppositely disposed faces 14, 14' in which are mounted pins 15, 16, which may be conveniently made of brass or other satisfactory material driven into the material of the hanger. These pins are of comparatively short length and serve as supports for the clamps constituting a particularly valuable portion of the invention.

A preferred form of the invention is illustrated in Figs. 1 and 2, and these figures should now be referred to.

Two clamping rods 17, 17' are suspended from the pins 15, 16 in such a manner that they cannot be materially displaced with respect to each other in a longitudinal direction, and so that they cannot be dislodged from the pins accidentally. As suspension means for these clamping rods, I prefer to use wire springs 18, which are provided at their mid-portions with a single coil 19 and have the ends 20 of the shanks bent at right angles. The shanks provide adequate space between the rods for the reception of the garments that are to be suspended.

The ends of the rods 17, 17' are slotted, in the form of the invention being described, at 21, and the bent ends 20 of the spring shanks are received in the slots and forced into the material of which the rods are made, as shown in Fig. 4. The rods may satisfactorily be made of wood or other material capable of receiving the ends of the springs. After the end of the spring has been thus seated in the end of a rod, the slot may be filled with

a material, such as plastic wood or other hardening compound, or with a plug 22. Plastic wood or the like has its own adhesive powers, whereas a plug usually requires gluing. Therefore, plastic wood is preferred. In this way, the springs are simply and inexpensively mounted in the ends of the rods and will perform their intended functions for extended periods of time.

The coil 19 may have as many turns as is desired, although one turn is generally sufficient if the spring has sufficient strength, which need not be great. The shanks of the spring are crossed in order to draw the rods 17, 17' into gripping relation, and they are also crossed in such manner as to prevent the rods from being displaced longitudinally with respect to each other. This is accomplished, as shown in the drawing, by bringing the shanks which support one rod inside the shanks which support the other rod. Thus, in Fig. 1 the shanks which support the visible rod are outside the shanks which support the hidden rod so that displacement of the latter with respect to the former is limited by the engagement of the spring shanks. This is achieved by bringing the shank of the inner turn of the spring coil outside the shank of the outer turn, which also serves to mutually brace the springs so that they will not be accidentally displaced from the pins 15, 16. Before they can be displaced, one of the springs 18 must be bent inwardly against its own resistance far enough to clear the end of the supporting pin. That resistance is ordinarily sufficient to prevent accidental disengagement, but is insufficient to offer any substantial impediment to intentional removal. It is therefore apparent that this structure provides the rods with clamping action, prevents them from being longitudinally displaced with respect to each other, and prevents the springs from being disengaged from the hanger accidentally.

An alternative method of attaching the ends of the spring shanks to clamping rods, and an alternative form of clamping rod, is shown in Figs. 5 and 6. In those figures the clamping rods 30 are square and are provided near their ends with annular grooves 31. The end 32 of the spring shank 33 is formed as a loop that fits within the slot 31. The portion of the slot beyond the spring may be filled with plastic wood or other hardening compounds to provide a smooth surface.

In Figs. 7 and 8 are shown other modifications. In these figures the numeral 40 indicates clamping rods of irregular shape, being somewhat L-shaped in cross section as shown in Fig. 7, leaving a space 41 at the top which is desirable in the suspension of trousers having cuffs. The cuffs may be put above the meeting faces 42 in the slot 41 provided for them, thus preventing the mar-ring of the cuff surface by the pressure of the hanger. The thickness of the cloth in the trouser leg above the cuff, being materially less than the thickness of the cloth in the cuff, is far less apt to retain an impression of the hanger. The springs 43, in this form of the invention, are seated in slots 44 which are cut in the outer and lower faces of the rods. This slot is thus L-shaped. The end 45 of the spring is three times bent. Once at 46, again at 47, and a third time at 48, the end 48 being driven into the material of which the rod is made, and the slot outside the spring being filled with a hardening material.

Fig. 9 represents an alternative form of the invention. In this form, two rods 50, 50' are supported at the lower end of levers 51, 51' that are pivoted together at their upper ends 52 and are drawn together by a spring 53 having hooked ends

engaged in holes 54 in the levers. A wire loop 55 serves to suspend the levers and the rods from the pins.

In all the forms of the invention which are being described, it is to be understood that other supports than pins may be employed to hold the removable section of the hanger. Thus, hooks may be employed in replacement thereof, and the ends of the hanger itself may be so shaped that they hold the suspending loop of the spring or wire. These suggested modifications are merely illustrative.

In Fig. 10 is a modification of the invention that does not require springs, but which yet attains a clamping action. In this form of the invention a pair of plates 60 are connected together by rods 61, 61' and are supported from the pins of the hanger by hooks 62. In these plates are a pair of converging slots 63, 63', in which are mounted rods 64, 64' having heads 65, 65'. The heads are of sufficient size to prevent the rods from being dislodged from the slots. The slots may be provided at their upper ends with enlarged portions 66 adapted to admit the heads, or the heads themselves may be made removable at one end, as by screw threading. The immovable rods 61 may be dispensed with by providing rods 64 with grooves in the ends in which the edges of the slots 63 are seated. In this way the plates 60 are attached to each other by means of the rods 64, 64' only. This suggested modification is of less importance than that which is illustrated because of the tendency of such construction to jam when the plates 60 are out of alignment.

In Fig. 11 is shown yet another modification of the invention, in which there are provided end plates 70 between which extends a rod 71 which is permanently attached to them. In addition, the device of Fig. 2 may be employed therewith, the loop 19 being arranged to coincide with an opening 72 in the plate 70 for hanging purposes. The bars 17 and 17' cooperate with the bar 71 to form a plurality of clamps. The plate 70 is of spring steel, preferably, and the opening 72 is surrounded by an annular boss upon which the loop 19 hangs. The devices of Figs. 10 and 11 can be fixed to the hanger if desired, although thereby they lose the removable feature that is an important advantage of this hanger construction.

The removable hangers are useful not only with a shoulder piece, but also separately. It is possible to construct in a closet or other suitable locations a series of pins, hooks or other supports that will receive and support the clamps by means of the supporting springs or brackets. This particular separate use is particularly valuable in clothing stores where trousers are suspended in display groups.

The shoulder section of the hanger may be molded out of plastic material, including the supports for the suspended section. The hook 13 may, in such cases, be molded of the same material of which the shoulders are molded, or may be a separate part molded into the neck. Similarly, the springs 18 may be molded at their ends into plastic members such as 17, 17'.

Several advantages of the invention have been pointed out in connection with certain features of its construction. In addition, it is noteworthy that the invention is of simple construction and is adapted to manufacture at low cost in large quantities, and that it is more efficient than the hangers of the prior art.

Another advantage of the invention is that the

clamping rods maintain their gripping action upon the clothing whether suspended or not and require no slider or camming member to force them into engagement with each other.

An advantage of the modifications shown in Figs. 5 and 7 is that the flat faces of the rods have less tendency to mar the garments between them.

As many apparently widely different embodiments of this invention may be made without departing from the spirit and scope thereof, it is to be expressly understood that the invention is not limited to the embodiments thereof herein illustrated and described except as defined in the appended claims.

What is claimed is:

1. A garment hanger comprising shoulder pieces, pins projecting from the underside thereof to serve as supports, clamping rods, and coil springs having crossed ends attached to the rods whereby to impart gripping action thereto, said springs having portions intermediate their ends formed into coils for supporting engagement with said pins, and the tip portions of said spring ends being embedded in said rods to support the latter and hold the same against movement longitudinally of said spring ends.

2. A garment hanger comprising shoulder pieces, pins projecting from the underside thereof and directed toward each other to serve as supports, clamping rods, and coil springs having crossed ends stiffly attached to and projecting from the rods whereby to impart gripping action thereto and to resist bending along the rods, said springs having intermediate supporting parts for engagement with the pins, resilient deflection of said supporting parts being required to hang the rods on, or to remove them from, the said pins.

3. A garment hanger including shoulder pieces, pins projecting from the shoulder pieces, clamping rods, springs having suspending parts engageable with said pins, said rods being connected at each end by said springs stiffly connected to the rods but having resilience laterally of the rods, so that the rods may be parted, and having resilience longitudinally of the rods, so that the suspending parts may be sprung over the pins for engagement with or removal therefrom.

4. A garment hanger comprising a supporting bar, two elongated clamping rods, and means for yieldably biasing said rods toward each other and for suspending the same in parallel side by side relation at equal distances below said supporting bar, said means comprising two stiff wire springs each having the center portion thereof formed into a coil and the end portions thereof connected to said rods, the connections between said end portions and rods being such as to hold the rods against movement longitudinally of said end portions, and means on said supporting bar extending into said coils to pivotally support said springs and rods.

5. A garment hanger comprising a supporting bar, two straight elongated clamping rods of substantially equal length, and means for suspending said rods side by side and with end to end contact with each other below and in spaced relation to said bar, said means comprising two stiff wire springs each having the center portion thereof formed into a coil and the end portions

thereof crossed, said springs being supported adjacent opposite ends of said bar for pivotal movement about a common axis parallel to said rods by means on said bar extending into said coils, an end of each spring having direct connection with one of said rods and the other end of each spring having direct connection with the other said rod, whereby said rods are yieldably biased into engagement with each other by said springs and held against movement longitudinally of said ends of said springs.

6. A garment hanger as defined in claim 5 wherein said rods have curved engaging side surfaces in substantially line contact with each other.

15 7. A garment hanger as defined in claim 5 wherein said ends of the springs extend longitudinally into the upper edges of said rods and have deformed tip portions engaging the rods to secure the latter against removal from the spring ends.

20 8. A garment hanger as defined in claim 7 wherein each said tip portion is wholly within the confines of the surface of a said rod and constitutes the sole means for securing the rod to the spring.

25 9. A garment hanger as defined in claim 7 wherein said tip portions are bent to extend at approximately right angles to the remainder of said spring ends and are embedded in the rods in the direction of the longitudinal axes of the latter.

30 10. A garment hanger as defined in claim 7 wherein the ends of the rods are slotted to receive said end tip portions and means filling said slots to help retain said portions in position.

35 11. A garment hanger as defined in claim 7 wherein said rods have angular grooves therein to receive the ends of the springs and said tip portions are curled to at least partially encompass the rods in said grooves.

40 12. A garment hanger as defined in claim 5 wherein the supporting means on the bar for said springs are so constructed and arranged that said coils are readily removable therefrom for disconnecting the spring and rod assembly from the bar.

45 13. A garment hanger as defined in claim 4 comprising a third rod suspended from said bar between said clamping rods, and wherein the latter are biased by said springs against opposite sides of said third rod.
